John Hickman, Lancaster, State of Ohio

Alleg. Patent.

The schedule referred to in these Letter, Patent and making part of the same containing a description in the words of the said John Hickman himself of his improvement in Bedstead fastenings.

To all persons to whom these presents shall come, John Hickman of Lancaster, Fairfield County State of Ohio aforesaid, Do it known that the said John Hickman, has invented, constructed, made & applied to use a new & useful improvement not used or known before in the making & putting together & taking apart of bedsteads, called "a self fastening machine".

This improvement in putting bedsteads together and taking them apart consists of the following explanation of the drawing herewith attached & made a part of this description.

No. 1 is a socket which is let in the post. No. 2 is let in the rail, fastened by a pin having three quarters of an inch project, on which enters in No. 1 a sliding dovetail which makes the self fastening machine, it has a not bottom faced.

In testimony that the above is a true specification of my said improvement as above described I have hereunto set my hand this 26th day of April in the year of our Lord 1802,

Witness,

John D. Dietrich

J. D. Hickman 3
